(57) **CLAIM**

The ornamental design for set of simulative pads for orthodontic brackets, as shown and described.

DESCRIPTION

FIG. 1 is a perspective view of one member of a set of simulative pads for orthodontic brackets showing my new design;

FIG. 2 is a top plan view thereof shown on a reduced scale;
FIG. 3 is a front elevation thereof;

FIG. 4 is a side elevation thereof the side opposite being a mirror image;

FIG. 5 is a bottom plan view thereof;

FIG. 6 is a rear elevation thereof;

FIG. 7 is a perspective view of a second member of a set of simulative pads for orthodontic brackets;

FIG. 8 is a top plan view thereof shown on a reduced scale;
FIG. 9 is a front elevation thereof;

FIG. 10 is a side elevation thereof the side opposite being a mirror image;

FIG. 11 is a bottom plan view thereof;

FIG. 12 is a rear elevation thereof;

FIG. 13 is a perspective view of a third member of a set of simulative pads for orthodontic brackets;

FIG. 14 is a top plan view thereof shown on a reduced scale;
FIG. 15 is a front elevation thereof;

FIG. 16 is a side elevation thereof the side opposite being a mirror image;

FIG. 17 is a bottom plan view thereof;

FIG. 18 is a rear elevation thereof;

FIG. 19 is a perspective view of a fourth member of a set of simulative pads for orthodontic brackets;

FIG. 20 is a top plan view thereof shown on a reduced scale;

FIG. 21 is a front elevation thereof;

FIG. 22 is a side elevation shown from the left side thereof;
FIG. 23 is a side elevation shown from the right side thereof;
FIG. 24 is a bottom plan view thereof;
FIG. 25 is a rear elevation thereof;
FIG. 26 is a perspective view of a fifth member of a set of
simulative pads for orthodontic brackets;
FIG. 27 is a top plan view thereof shown on a reduced scale;
FIG. 28 is a front elevation thereof;
FIG. 29 is a side elevation thereof the side opposite being a
mirror image;
FIG. 30 is a bottom plan view thereof;
FIG. 31 is a rear elevation thereof;
FIG. 32 is a perspective view of a sixth member of a set of
simulative pads for orthodontic brackets;

FIG. 33 is a top plan view thereof on a reduced scale;
FIG. 34 is a front elevation thereof;
FIG. 35 is a side elevation thereof the side opposite being a
mirror image;
FIG. 36 is a bottom plan view thereof;
FIG. 37 is a rear elevation thereof; and,
FIG. 38 is perspective view of the members of the claimed
invention in one exemplary intended environment.
The broken lines shown in the figure drawings are included
for the purpose of illustrating environment and form no part
of the claimed design.
